BENDABLE WAVE COMB

Neil Fulton, New York, N. Y.

Original application December 17, 1932, Serial No. 647,810. Divided and this application May 10, 1933, Serial No. 670,342

4 Claims. (Cl. 132—38)

The present invention relates to a device adapted to be used in hair-dressing or by professional hair-dressers or by individuals in the home and has for an object to provide a relatively simply constructed and inexpensive device which may be used in multiple for engaging the hair and holding it in waved form for a considerable period of time until the hair is set so that it will inherently remain in waved form after the combs are removed.

The present application is a division of my co-pending application for Wave combs Serial No. 647,810, filed Dec. 17, 1932.

Another object of the invention is to provide a wave comb of this character which possesses various characteristics hereinafter brought out and which at the same time may be constructed to conform to the general curvature of the head so as to lie flat against the head and form and maintain the hair and the waves in the general configuration of the head.

A further object of the present invention is to provide an inherently stiff and yet bendable comb which has teeth along one edge and adapted to be engaged by an edgewise movement into the hair in such position that the comb may lie flat against the side of the head and be bent to the general configuration of the head. This object also aims to provide a reinforcement for this bendable comb in the nature of a flange which extends outwardly at an angle to the comb and which is slotted at substantially spaced apart points to admit of the bending of the comb without flattening or breaking the flange. This flange is also utilized for receiving clips or other fastening devices for holding the comb of this invention in place when the comb is used in multiple as is common in hair waving.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a fragmentary perspective view of a bendable wave comb constructed according to the present invention.

Figure 2 is an inner edge elevation of a portion of the same, showing the strip bent to a desired curvature.

Figure 3 is an inner side elevation of a complete bendable wave comb constructed according to the present invention; and

Figure 4 is a transverse enlarged section

through one end of the same substantially on the line 4—4 of Figure 3.

As shown in the drawing, the comb member 60 is in the form of a flat strip having comb teeth 64 of desired size and spacing in one edge 60 of the flat strip, the teeth 64 adapted to engage in flat relation through the hair by an edgewise movement of the comb member 60.

The comb member 60 is provided along its inner edge with an outstanding flange 61 of suitable thickness and height to not only give the desired strength to the comb structure but to also receive on the upstanding flange 61 clips, clasps or other suitable fastening or binding devices which may be employed for securing a number of these comb members together to form waves in the hair, as in the other forms of the device disclosed in the parent application.

The comb member 60 is preferably of a bendable material, such as celluloid, metal, paper or the like, and the flange 61 is provided at suitable intervals with slits or cuts 62 which extend from the upper or outer edge of the flange 61 downwardly and inwardly to a point 63 in spaced relation from the lower edge of the flange or comb member. Thus, the thickness of the comb member 60 is left intact throughout its width and the flange 61 is given sufficient continuous support near its inner edge to provide a relatively strong and durable structure. At the same time, the slits 62 are of sufficient depth to admit of the bending of this comb structure lengthwise to conform to the curvature of the head.

It is obvious that various changes and modifications may be made in the details of construction and design of the above specifically described embodiment of this invention without departing from the spirit thereof, such changes and modifications being restricted only by the scope of the following claims.

What is claimed is:—

1. In a wave comb, a comb member having a tooth portion bendable lengthwise to conform substantially to the curvature of the head and adapted to lie flat thereagainst, said comb member also having a reinforcing and attaching flange extending outwardly at an angle from the tooth portion and provided with transverse slits admitting the bending of the tooth portion without flattening the flange.

2. A wave comb comprising a relatively flat bendable strip having teeth in one edge and adapted to be bent lengthwise in the general curvature of the head, and an outstanding flange carried by the strip for strengthening the same

and affording means of attachment of a plurality of the combs in group form in the hair, said flange having slits therein at spaced intervals extending inwardly from the free edge of the flange to admit bending of the flat comb strip without flattening or distorting the flange.

3. A bendable wave comb comprising a bendable strip having teeth in one edge and a flange at its other edge, said flange having slits therein at spaced points admitting bending of the strip to conform to the curvature of the head, said flange adapted to reinforce and stiffen the strip

and adapted to receive clamping devices for assembling a plurality of the wave combs in the hair.

4. A bendable wave comb comprising a strip of desired width and length having one edge portion upturned to provide a flange and having comb teeth in its opposite edge portion, said flange having slits therein at spaced points admitting of the bending of the toothed portion of the strip to the configuration of the head without distortion of said flange.
